CLAIM

We claim the ornamental design for a task shade stand, as shown and described.

DESCRIPTION

FIG. 1 is a front perspective view of a task shade stand of indeterminate length, showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is an additional perspective view of the task shade stand in use supporting a task shade; and,

FIG. 9 is an additional perspective view of the task shade stand in use supporting a task shade.

The task shade stand is shown with a symbolic break in its length. The appearance of any portion of the article between the break lines forms no part of the claimed design.

The broken lines in the drawings are included for the purpose of illustrating portions of the task shade stand and form no part of the claimed design.
